EDGE STITCHING PRESSER FOOT FOR
SEWING MACHINESFrank Vanadia and Carmen Rosetto,
New York, N. Y.

Application May 5, 1949, Serial No. 91,452

12 Claims. (Cl. 112—235)

2

This invention relates to new and useful improvements in a sewing machine presser foot, and, more particularly, the aim is to provide a novel and valuable such presser foot incorporating marked improvements in simplicity of structure, reliability of operation, ruggedness of parts, and long life throughout, and which is readily attachable to a standard manually raisable member of a sewing machine, and which, in an improved manner, affords a variety of utilities, a very important one of which is a capacity for insuring the laying down of a line of stitching exceedingly close to the edge of a piece of fabric, such for instance, as an edge marked by a fold of said fabric piece.

A feature of the invention is a novel and valuable construction of and mounting for the presser foot, for movement of the latter relative to a shank element provided in substitution for the usual upstanding shank integral with the conventional presser foot.

A further feature of the invention is a novel and valuable combination comprising the new presser foot and a uniplanar gauge plate, variously movable in its own plane in unison with or differentially from any movement of the new presser foot relative to said shank element.

Another feature of the invention is an improved resilient means for acting on the gauge plate to bias the same normally to a pre-determined disposition in a vertical plane.

Still a further object of the invention is the combination with a new presser foot of a novel thread-cutting attachment to be carried by the new assembly, and in such manner that a sharp portion of a cutting edge may be substantially instantaneously substituted for a previously dulled portion of said edge, all without removal of the cutting member from the presser foot.

Another object of the present invention proposes the provision of a novel means on the presser foot for holding the gauge plate in a raised inoperative position when it is desired to use the presser foot without the gauge plate.

It is a further object of the present invention to construct a presser foot which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front perspective view of a now favored embodiment of the new presser foot of the invention, looking slightly down on the same.

Fig. 2 is a view similar to Fig. 1, but looking from the other side of the presser foot.

Fig. 3 is a vertical section taken on the line 3—3 of Fig. 1.

Fig. 4 is an enlarged fragmentary detail view, showing certain of the parts as seen in Fig. 3, with a spring-urged plunger illustrated in axial section.

Fig. 5 is a rear elevation, showing one form of the new thread cutter attachment.

Fig. 6 is a view similar to Fig. 5, but showing modified form of such attachment.

Fig. 7 is a top plan view of a piece of fabric folded over on itself, and showing a stitching effected relative to the line of fold of said fabric piece, with said stitching exceedingly close to said line of fold, in particular illustration of a principal utility of the presser foot of the present invention.

Fig. 8 is a cross sectional view similar to Fig. 3, but illustrating the presser foot provided with means for holding the gauge plate in a raised inoperative position when desired.

Fig. 9 is a perspective view similar to Fig. 1, but illustrating the presser foot provided with a modified means for holding the gauge plate in a raised inoperative position.

Fig. 10 is a front elevational view of Fig. 9, but with the bottom portion thereof broken away.

Fig. 11 is an enlarged horizontal sectional view taken on the line 11—11 of Fig. 10.

Fig. 12 is a rear perspective view of the locking lever, per se.

Fig. 13 is a partial perspective view of the gauge plate and associated elements.

Referring to the drawings more in detail, the new presser foot assemblage is illustratively shown as including an upstanding presser foot shank 10. This shank or equivalent, ordinarily, or in most cases heretofore, has integrally carried the presser foot. In the present case, however, the presser foot is a foot 11 pivotally mounted near the rear end thereof and near the lower end of said shank for rocking about a horizontal axis.

The thus hung foot 11 is elongate, is of about the usual width, but is bifurcated in a direction parallel to its length along a line slightly offset from the center line of such length, thereby to

have the foot 11 present a wider presser finger 12 and a narrower but longer presser finger 14. The pin for pivotally mounting the presser foot 11 is indicated at 15. As will be seen from Figs. 1 and 2 the bottom curvatures of the fingers 12 and 14 are matchingly extended longitudinally of the presser foot.

In combination with this presser foot 11, and between the two fingers thereof, as in the placement illustrated, there is also present a thin uniplanar vertical gauge plate 16. This plate has a rear portion 17, which portion is substantially of rectangular shape but having a rounding 17a at its forward upper corner substantially matching a rotundity of a boss 18 formed on the lower end of the shank 10, and which boss is pierced to take the pivot pin 15.

Near the forward end of said portion 17 of the gauge plate 16 is a generally vertically extended slot 19, thereby to provide a pin-and-slot connection between the gauge plate and the pivot pin 15, whereby the gauge plate is floatingly coupled to the rockable presser foot.

Forward of a rearwardly facing shoulder or step-down 20 at the bottom of the gauge plate, the latter is shaped to present a frontal plate portion 21.

The shank, from its top to its bottom, is bored, as at 22, and said shank, near its bottom, is vertically milled in a straight fore and aft direction to provide an aligned pair of narrow vertical slots 23, 23, for accommodation therein of the portions of the gauge plate 16 passing through said shank.

For normally holding the gauge plate 16 and in turn the presser foot 11 to have substantially a horizontal direction of longitudinal extension, there is in the bore 22 a plunger 24 having a flat bottom for resting on the flat upper surface of the gauge plate in the rear of its pivot pin 15. This plunger or piston is topped by a reduced extension 25, with which is engaged the lower end of an expansile coil spring 26 held in place and given a predetermined normal tension by adjustment of a set-screw 27. The opposite end portions of the pivot pin 15 are journaled in a rearward extension 28 of the presser foot 11, preferably of U-shaped cross-section as illustrated and providing a trough-like cup.

The long thin slit separating the presser foot fingers 12 and 14, for allowing the laying down of a top thread during a stitching operation is interrupted by a half-round aperture 29, formed in the wider and shorter finger 14, for rise and fall of the lower end of the needle therethrough.

A novel attachment for quick thread cutting is also carried by the shank of the presser foot, this attachment comprising a shaped carrier plate 30, mountable at the back of said shank, and swingably adjustable as thus mounted, by a screw 31 having its shank passed through a suitable aperture in said plate and then entered into a drilled and tapped recess in said shank. The outer portion of said plate, which is here shown as roughly U-shaped, is forked to provide a slot 32 along which a thread to be cut may be passed. A cutter blade 33 having opposite its cutting edge 34 an open-ended slot 35, is mounted on the plate 30 by means of a screw 36, the shank of which passes through the slot 35 and into a tapped recess in the plate 30, the arrangement being such that from time to time a part of the length of the cutting edge 34 at the effective bottom of the slot 32 may be readily varied as such edge portion becomes dulled in use, and hence a single

sharpening of said edge 34 may serve for a very long period of time.

Referring to the modified cutter attachment illustrated in Fig. 6, in which view the parts outlined in dot and dash lines, and to which are applied reference numerals with primes added, correspond, respectively, to the parts to which have been applied the same reference numerals without primes. Here, a simplified form of cutter attachment is shown, the same comprising a single shaped plate 37 having downwardly extended from the top of its main portion an open-ended slot 38, this for taking the shank of a screw 39, which shank is also received in a drilled and tapped recess in the rear portion of the shank of the presser foot assembly 10'. Said plate 37 has a generally upwardly and outwardly inclined extension 40 carrying at its upper margin a preferably curvilinearly extended cutting edge, such as indicated at 41.

Adverting to Figs. 1-3, the shank of the presser foot assemblage near its top, and rearwardly projected therefrom, integrally carries a formation 42 constituting, pursuant to usual practice, a convenient means for participating in the attachment of the presser foot assemblage to the manually raisable member located adjacent the needle carrier, said formation, as here shown, having a back wall 43 integral with a web 44 integral with the main body of the presser foot shank; said web 44 having an open-ended downwardly extending slot 45 for extension therethrough of the shank of a suitable attaching screw or the like.

In Fig. 7, a piece of fabric 46 is illustrated as having had applied thereto a stitching 47 exceedingly close to the line of fold 48 of said fabric piece. Such a result, made possible by the presser foot of the present invention, has long been sought to be attained in a practicably simple presser foot structure, such as here shown. The gauge plate 16 may move up and down against the spring 26, in view of the pin-and-slot connection 15-19, and thus cling close to the top of the fabric, but nevertheless is able to move up and down bodily as the fabric is passing under the presser foot. The presser foot itself, at the same time, is rockable about said pin 15. The presence of these parts, in the arrangement described, plus the relationship of the center of the half-round aperture 29 to the near side of the gauge plate 16, permits such stitching as that shown at 47 to be easily and rapidly and perfectly established, even with the sewing machine power-driven and operating at a very high rate of speed, since all that is required is to guide the fabric so that the line 47 thereof is held over against that side of the presser plate which is the near side thereof in Fig. 2.

The step-down 20 is very important, as with it present, in the normal operation of the sewing machine the bottom of the gauge plate 16 ahead of said step-down will never rise above the bottom surface of the main portion of the presser foot 11, and as a result the gauge plate is always effective to keep the line 47 moving along its appointed rectilinear path of travel.

In the modification of the invention shown in Fig. 8, the construction of the presser foot is similar to that shown in Figs. 1 to 4, except for the provision of a means for holding the gauge plate 16 in a raised inoperative position when desired.

The holding means is characterized by a screw 50 which is threaded into the rear of the shank 10' of the presser foot assembly at an inclina-

tion as clearly shown on the drawings. The outer end of the screw 50 is formed with an enlarged knurled head 51 by which the screw can be conveniently turned. An expansion spring 52 is coaxially wound on the shank of the screw 50 and operates between the shank 10' and the enlarged head 51 so as to retain the screw 50 in any position into which it might be turned.

The plunger 24' of the gauge plate 16 is formed with a cutout 53 which is faced rearward and which has an upper inclined surface 54 extended parallel to the inner end of the screw 50. When the gauge plate 16 is in its completely lowered position shown in Fig. 8, the top end of the inclined surface 54 slightly overlaps the inner end of the opening into which the screw 50 is threaded so that when the screw 50 is turned inward, its inner end will catch on the surface 54. As inward turning of the screw 50 is continued the inclined surface 54 will ride over the inner end of the screw causing the gauge plate 16 and the plunger 24' to be raised to an inoperative position against the action of the spring 25. In its completely raised inoperative position, the bottom edge of the gauge plate 16 will be flush with or raised slightly above the bottom face of the presser foot 11.

In other respects this form of the invention is similar to that shown in Fig. 1 to 4 and like reference numerals identify like parts in each of the several views.

In the further modified form of the invention shown in Figs. 9 to 13, the construction of the presser foot assembly is again similar to that shown in Figs. 1 to 4, except that it is provided with a different means for holding the gauge plate 16 in a raised inoperative position.

This further modification is characterized by the fact that the gauge plate 16 is secured to the side of a block 60 by several rivets 61. The block 60 is disposed for vertical sliding movement in a cutout 62 which opens to the front face of the shank 10'', as clearly shown in Figs. 9 to 11. The top end of the block 60 is provided with the plunger 24'' which is to be engaged by the spring 26, see Figs. 10 and 13. Extending from the block 60 and beyond the front face of the shank 10'' there is a projection 63.

Projecting laterally from one side of the shank 10'' there is a lug 64 upon which a locking lever 65 is pivotally mounted by means of screw 66. The inner side of the locking lever 65 is formed with a lip 67 which lies beneath the projection 63 as clearly illustrated in Figs. 9 and 10. Extending rearward from the top edge of the locking lever 65 there is a lug 68 which limits movement of the locking lever to operative and inoperative positions. When the locking lever 65 is in the inoperative position shown in Fig. 9 the lug 68 abuts the side of the shank 10'' and when the locking lever is in the operative position shown in Fig. 10 the lug 68 rests on the top face of the lug 64.

The lug 64 outward of the screw 66 is formed with a hollow 69, see Fig. 11, in which a ball 70 is located. A spring 71 is also positioned within the hollow 69 and operates between the ball 70 and the back wall of the hollow 69 for urging the ball forward. When the locking lever 65 is in the inoperative position shown in Fig. 9, an edge portion of the locking lever 65 overlies the ball 70 and retains it against being discharged from the hollow 69 by the spring 71.

At one point, the back face of the locking lever 65 is formed with a recess 72 into which the ball 73

70 is engaged when the locking lever is in the operative position shown in Fig. 11 so as to hold the locking lever in that pivoted position. The locking lever 65 is further formed with an inclined guide surface 73, see Fig. 12, for guiding the ball 70 into the recess 72 as the locking lever 65 is pivoted from the inoperative position shown in Fig. 9 to the operative position shown in Figs. 10 and 11. In the inoperative position the bottom edge of the gauge plate 16 is flush with the bottom face of the pressure foot 11.

In assembling the pressure foot shown in Fig. 9 to 13, the gauge plate 16 with the attached block 60 is slipped into position in the open front of the cutout 62 prior to the attachment of the presser foot 11 by means of the pin 15.

In other respects the form of the invention shown in Figs. 9 to 13 is also similar to that shown in Figs. 1 to 4 and like parts are identified 20 by the same reference numeral.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. A sewing machine presser foot comprising a presser foot shank, an elongate presser foot pivotally mounted near its rear end on said shank near the lower end thereof, such mounting including a horizontal pivot pin extended at right angles to the length of the presser foot, said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin.

2. A sewing machine presser foot comprising a presser foot shank, an elongate presser foot pivotally mounted near its rear end on said shank near the lower end thereof, such mounting including a horizontal pivot pin extended at right angles to the length of the presser foot, said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being

slotted, and said plate having a tail portion extended into said slot, said spring means for imparting a downward thrust effective on said tail portion.

3. A sewing machine presser foot comprising a presser foot shank, an elongate presser foot pivotally mounted near its rear end on said shank near the lower end thereof, such mounting including a horizontal pivot pin extended at right angles to the length of the presser foot, said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slideable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said cavitation being a well-like chamber extending lengthwise of said shank, and there being in said chamber a plunger upon the lower end of which said gauge plate is mounted, said spring being an expansile coil spring directly acting downwardly on said plunger.

4. A sewing machine presser foot comprising a presser foot shank, an elongate presser foot pivotally mounted near its rear end on said shank near the lower end thereof, such mounting including a horizontal pivot pin extended at right angles to the length of the presser foot said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slideable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extending into said slot, said spring means for imparting a downward thrust effective on said tail portion, said cavitation being a well-like chamber extending lengthwise of said shank, and there being in said chamber a plunger upon the lower end of which said gauge plate is mounted, said spring being an expansile coil spring directly acting downwardly on said plunger, there being a member for reacting against the upper end of said spring and for adjusting its tension, said member being a screw threadedly entered into the top of said shank.

5. A sewing machine presser foot comprising

a presser foot shank, an elongate presser foot pivotally mounted near its rear end on said shank near the lower end thereof, such mounting including a horizontal pivot pin extended at right angles to the length of the presser foot, said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slideable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said aperture being wholly inset in one of said fingers at the side thereof facing said slit, and said slit being of a width approximately equal to the radius of said aperture.

6. A sewing machine presser foot comprising a presser foot shank, an elongate presser foot pivotally mounted near its rear end on said shank near the lower end thereof, such mounting including a horizontal pivot pin extended at right angles to the length of the presser foot, said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slideable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said aperture being wholly inset in one of said fingers at the side thereof facing said slit, and said slit being of a width approximately equal to the radius of said aperture, said gauge plate being of a thickness amounting to a very small fraction of the width of said slot.

7. A sewing machine presser foot comprising a presser foot shank, an elongate presser foot pivotally mounted near its rear end on said shank near the lower end thereof, such mounting including a horizontal pivot pin extended at right angles to the length of the presser foot, said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar ver-

tically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said gauge plate having a rearwardly facing step-down at a point along its bottom and intermediate its ends.

8. A sewing machine presser foot comprising a presser foot shank, an elongate presser foot pivotally mounted near its rear end on said shank near the lower end thereof, such mounting including a horizontal pivot pin extended at right angles to the length of the presser foot said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said cavitation being a well-like chamber extending lengthwisely of said shank, and there being in said chamber a plunger upon the lower end of which said gauge plate is mounted, said spring being an expansile coil spring directly acting downwardly on said plunger, there being a member for reacting against the upper end of said spring and for adjusting its tension, said member being a screw threadedly entered into the top of said shank, and means for holding said gauge plate in a raised inoperative position with relation to said presser foot.

9. A sewing machine presser foot comprising a presser foot shank, an elongate presser foot pivotally mounted near its rear end on said shank near the lower end thereof, such mounting including a horizontal pivot pin extended at right angles to the length of the presser foot said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrust-

ing spring means in such cavitation, said shank also being slotted, and said plate having a tail portion extended into said slot, said spring means for imparting a downward thrust effective on said tail portion, said cavitation being a well-like chamber extending lengthwisely of said shank, and there being in said chamber a plunger upon the lower end of which said gauge plate is mounted, said spring being an expansile coil spring directly acting downwardly on said plunger, there being a member for reacting against the upper end of said spring and for adjusting its tension, said member being a screw threadedly entered into the top of said shank, and means for holding said gauge plate in a raised inoperative position with relation to said presser foot, said holding means comprising a screw threaded into the presser foot shank at an inclination, said plunger being formed with a cutout having an inclined surface arranged parallel to the inner end of said screw to be engaged by the inner end of said screw when turned inward for camming said plunger and the attached gauge plate upward to an inoperative position.

10. A sewing machine presser foot comprising a presser foot shank, an elongate presser foot pivotally mounted near its rear end on said shank near the lower end thereof, such mounting including a horizontal pivot pin extended at right angles to the length of the presser foot said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said cavitation being a well-like chamber extending lengthwisely of said shank, and there being in said chamber a plunger upon the lower end of which said gauge plate is mounted, said spring being an expansile coil spring directly acting downwardly on said plunger, there being a member for reacting against the upper end of said spring and for adjusting its tension, said member being a screw threadedly entered into the top of said shank, and means for holding said gauge plate in a raised inoperative position with relation to said presser foot, said holding means comprising a screw threaded into the presser foot shank at an inclination, said plunger being formed with a cutout having an inclined surface arranged parallel to the inner end of said screw to be engaged by the inner end of said screw when turned inward for camming said plunger and the attached gauge plate upward to an inoperative position, and means for holding said screw in a desired adjusted rotative position.

11. A sewing machine presser foot comprising a presser foot shank, an elongate presser foot pivotally mounted near its rear end on said shank

near the lower end thereof, such mounting including a horizontal pivot pin extended at right angles to the length of the presser foot said presser foot being bifurcated along its forward portion to provide a pair of forwardly extending presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said cavitation being a well-like chamber extending lengthwise of said shank, and there being in said chamber a plunger upon the lower end of which said gauge plate is mounted, said spring being an expansile coil spring directly acting downwardly on said plunger, there being a member for reacting against the upper end of said spring and for adjusting its tension, said member being a screw threadedly entered into the top of said shank, and means for holding said gauge plate in a raised inoperative position with relation to said presser foot, said holding means comprising a block forming part of said plunger and to which said gauge plate is attached, a projection extending from said block beyond the front face of said shank, a locking lever pivotally mounted on said shank and having a lip underlying the projection, and means for holding said locking lever in a pivoted position in which the block and attached gauge plate will be in a raised inoperative position.

12. A sewing machine presser foot comprising a presser foot shank, an elongate presser foot pivotally mounted near its rear end on said shank near the lower end thereof, such mounting including a horizontal pivot pin extended at right angles to the length of the presser foot said presser foot being bifurcated along its forward portion to provide a pair of forwardly extending

presser fingers separated by an intervening slit, the presser foot having an aperture therethrough in vertical alignment with the path of up and down travel of the needle of the sewing machine, said aperture at its location constituting a localized widening of said slit, and a uniplanar vertically disposed gauge plate slidable on said shank and extended forwardly into and along said slit to narrow the same, said gauge plate having a generally up and down extending slot through which said pivot pin extends, whereby said plate is free to be bodily movable in an up and down direction relative to said pin, said shank being cavitated, and there being a downwardly thrusting spring means in such cavitation, said shank also being slotted, and said plate having a tail portion extended into said slot, said spring means for imparting a downward thrust effective on said tail portion, said cavitation being a well-like chamber extending lengthwise of said shank, and there being in said chamber a plunger upon the lower end of which said gauge plate is mounted, said spring being an expansile coil spring directly acting downwardly on said plunger, there being a member for reacting against the upper end of said spring and for adjusting its tension, said member being a screw threadedly entered into the top of said shank, and means for holding said gauge plate in a raised inoperative position with relation to said presser foot, said holding means comprising a block forming part of said plunger and to which said gauge plate is attached, a projection extending from said block beyond the front face of said shank, a locking lever pivotally mounted on said shank and having a lip underlying the projection, and means for holding said locking lever in a pivoted position in which the block and attached gauge plate will be in a raised inoperative position, said holding means comprising a spring pressed ball mounted on said shank for engaging a complementary recess formed in said locking lever.
